(57) **CLAIM**

The ornamental design for an inkjet cartridge protect clamp, as shown and described.

DESCRIPTION

FIG. 1 is a perspective view of an inkjet cartridge protect clamp showing my new design;

FIG. 2 is a front elevational view;

FIG. 3 is a rear elevational view;

FIG. 4 is a left side elevational view;

FIG. 5 is a right side elevational view;

FIG. 6 is a top plan view;

FIG. 7 is a bottom plan view; and,

FIG. 8 is a side elevational view.

The broken lines in FIG. 8 are for illustrative purposes only and form no part of the claimed design.
